MONUMENT

Horace B. Compton, Scotia, N. Y.

Application July 6, 1936, Serial No. 89,203

1 Claim. (Cl. 189—21.2)

This invention relates to monuments or grave markers and an object of the present invention is to provide a monument of metal which will be capable of being cheaply and economically constructed, quickly and easily assembled at the grave or site of use, and which also will be rust-proof.

The invention together with its objects and advantages will be best understood from a study of the following description taken in connection with the accompanying drawings wherein:—

Figure 1 is a front elevational view of a monument embodying the features of the present invention, the monument being shown set up for use.

Figure 2 is a side elevational view of the monument.

Figure 3 is a top plan view of the monument.

Figure 4 is a sectional view taken substantially on the line 4—4 of Figure 3.

Figure 5 is a front elevational view of the panel section of the monument.

Figure 6 is a plan view of the base section of the monument.

Figure 7 is a sectional view taken substantially on the line 7—7 of Figure 2.

Figure 8 is a sectional view taken substantially on the line 8—8 of Figure 5.

Referring to the drawings by reference numerals it will be seen that broadly the improved monument comprises a base 5 upon which is mounted a slab or panel section 6.

The slab or panel section 6 is of hollow construction and comprises substantially rectangular front and back sheets 7 and 8, respectively, narrow elongated side sheets 9, and a top sheet 10.

The sheets 7, 8, 9 and 10 are of rust resisting metal and at the joints between the sheets said 40 sheets are welded together as at 11.

The base 5 comprises a hollow shell-like casting of rust resisting metal and including side walls 12, end walls 13, a bottom wall 14, and a top wall 15, the walls at the joints thereof being 45 welded together as indicated generally at 16.

The top wall 15 is provided with an opening 17 of a size slightly larger than the panel 6 so as to permit the lower portion of the panel 6 to fit within the opening 17 as shown in Figure 4.

50 The walls 7, 8, and 9 at their lower edges are adapted to be welded to the plate 15 of the base

5 at the edge of the opening 17 as indicated at 18.

From the description of the invention thus far it will be seen that the plates of which the base 5 and panel 6 are formed may be shipped to the site of use and the plates there assembled and welded together to form respectively the base 5 and the panel 6.

Also, and as shown in Figure 4, the base 5 is adapted to contain therein to its full capacity 10 concrete or the like 19 which will add to the weight of the monument and serve to hold the monument anchored in position. In this connection it will be understood that the concrete 15 19 may be poured into the base 5 after it has been set up and prior to the welding of the walls of the panel 6 to the top 15 of the base.

Of course, it will be understood that if desired the plates forming respectively the base 5 and panel 6 may be welded and joined together prior 20 to shipment, the base 5 and panel 6 of course remaining separated, if found desired, until the monument is to be actually set up at the place of use.

It is thought that the construction, utility and advantages of a monument or tomb marker, providing the features of the present invention will be understood without a more detailed description.

Having thus described the invention what is 25 claimed as new is:—

A monument or tomb marker comprising a base having a bottom, side and end walls, and a top wall, all of said walls being formed of rust resisting metal and welded at the joints to provide a hollow shell-like structure, and a panel adapted to be mounted on and supported by said base and comprising a front wall, a rear wall, side walls, and a top wall, all of said walls being 30 formed of rust resisting metal and welded together at the joints to provide a hollow shell-like structure open at its bottom, the top of said base being provided with an opening through which concrete or the like may be placed within 35 said base, and the said panel having its open bottom end inserted through and snugly fitting the opening in the top of the base and resting on the concrete with a weld joint at the juncture of the base and the panel.

HORACE B. COMPTON.
